RESILIENT INSERT-INSOLE COMBINATION

Meyer Margolin, Elgin, Ill.

Application February 3, 1941, Serial No. 377,948

2 Claims. (Cl. 36—3)

My invention relates to a novel resilient shoe insole and more particularly my invention relates to a novel combination of insole, outsole and filler, which combination is adapted to provide increased foot comfort in that a softer and more resilient cushion is provided for the foot and increased breathing and ventilation effected.

One form of my invention which I shall describe more specifically hereinafter is adapted to be employed in that type of shoe in which the insole is formed by splitting off a layer of leather from the outsole. The insole may be split from the outsole to provide a thin insole and a relatively thicker outsole, or the cleavage may be so effected as to provide a raised portion or island on the top or upper side of the outsole with a corresponding dished out concavity on the lower side of the insole. This raised portion or island may be so cut that the dished out concavity in the insole extends through the thickness of the insole and forms an opening in the center forepart thereof.

It is also within the purview of my invention to provide a metatarsal support element which is formed integrally with the filler and disposed in the proper position thereon.

The advantages of the constructions as outlined above are manifold. First, I provide for a greatly increased flexibility in the outsole-insole combination and this flexibility is greatest in the center of the forepart of the insole where such flexibility is desired. Second by my construction I provide for greatly increased resilience and softness of step for the shoe employing this construction and this resilience and softness is greatest at the ball portion of the foot which is adapted to take the impact of the foot in walking. The resilience tapers down from this ball portion to the peripheral portion of the filler where the filler approaches a feather edge thinness. Third, my construction provides for increased ventilation and breathing in these shoes of the so-called one piece sole type.

This application is a continuation in part of my copending application Serial No. 306,778, filed Nov. 30, 1939, for Novel insole and outersole combination.

It is the object of my invention to provide a novel resilient combination of outsole, insole and filler.

It is a further object of my invention to provide a novel filler for a so-called one piece sole.

These and further objects of my invention will become apparent from a consideration of the

drawing and the specific description thereof which here follows:

Figure 1 is a central longitudinal cross section of a form of my invention.

Figure 2 is a top plan view of the form of my invention shown in Figure 1.

Figure 3 is a transverse cross section along the line 13—13 of Figure 2.

Figure 4 is a central longitudinal cross section of another modified form of my invention.

Figure 5 is a central longitudinal cross section of another modified form of my invention.

Figure 6 is a top plan view of the modified form of my invention shown in Figure 5.

In Figure 1 I show a construction by means of which I provide increased shoe comfort. An outsole 60 and an insole 61 which has been split from the outsole so that an island or raised portion 62 is provided in the center forepart of the outsole, are joined after the upper 64 is lasted to the insole 61 in the usual manner. A resilient pad 65 is secured to the insole 61 by stitching 66 and 67. I may provide on the resilient pad an integral metatarsal support 69. The resilient pad 65 is provided with grooves 70 and perforations 71. Additionally I may provide grooves 73 which communicate upwardly with the interior of the shoe by means of perforations 74. Where the perforations 71 overlie the insole 61 I may further provide perforations 76 in the insole 61 by means of which perforations I achieve two new and unexpected results. First, the insole is rendered more flexible and secondly I provide increased breathing properties for the shoe in that air is circulated through the insole and through the resilient pad and air pockets of increased depth and volume are provided by these perforations 76 in the insole 61.

The resilient pad 65 may extend as shown from the toe portion of the longitudinal arch or it may extend for the full length of the shoe from toe to heel. By employing resilient pads of different thicknesses I may make adjustments in the shoe as desired. Thus, I may provide a snugger fit for the shoe. However, the resilient pad and the perforations therein together with the perforations in the insole directly below and matching the perforations in the resilient pad have great value for the increased breathing, coolness and flexibility imparted thereby.

Figure 2 is a plan view of this resilient pad-insole construction showing the relative position of the components of the assembly.

In Figure 4 I show an ordinary outsole 178 which is secured to the insole 171 after the upper

72 has been lasted to the insole 171. Superimposed upon the insole 171 is a resilient pad 173 having perforations 174. In the insole 171 are located perforations 175 which are positioned to constitute extension of perforations 174 and provide air pockets of increased volume. Perforations 175 also make for greater flexibility and lightness of the insole. In addition to the perforations 174 in the resilient pad, I may also provide grooves 177 and combination grooves and perforations 178. A molded metatarsal arch support 80 may also be provided on the resilient pad and the resilient pad may be secured to the insole 171 by any suitable means such as cement or stitching or the resilient pad 173 may be adapted to merely lie in frictional engagement with the insole 171.

In Figure 5 I show a resilient pad 82 which is adapted to act both as a means for increased ventilation, breathing and resilience and also as a size pad if desired in that by varying the thickness of the pad 82 various volumetric adjustments can be made within the shoe. The resilient pad 82 has perforations 83 which are adapted to coat with and lie superimposed over corresponding perforations 84 in the resilient insert 85 which is secured to the insole 86 by stitching 87. Certain perforations 88 in the resilient pad 82 are adapted to lie in communication with the combination perforations and grooves 90 in the insert 85. In other instances I may provide combination perforations and grooves 92 in the resilient pad which are in communication with combination perforations and grooves 83 in the insert. The outsole 85 is secured to the insole 86 after the upper 96 has been lasted to the insole.

I may further provide in the resilient pad 82 a molded metatarsal arch support 97 having perforations 98 therein and in the insert 85 I may also provide a metatarsal arch support 100 having perforations 101 which are adapted to be positioned adjacent perforations 98 in the resilient pad. I may provide lugs 103 which are integral with and extend downwardly from the resilient pad 82 and are adapted to engage corresponding recesses 104 in the resilient insert 85.

As shown in Figure 6, where the resilient pad 82 extends over the insole 86, perforations 106 in the resilient pad may coat with corresponding perforations 107 in the insole 86 to provide air pockets of increased volume for better ventilation and breathing of the shoe and also to increase the flexibility of the insole.

It is to be understood that the resilient pad adapted to produce increased breathing, resilience and foot comfort, above specifically de-

scribed, may be secured to the underlying insole or composite insole in any desired manner.

The combination of perforations in the resilient pad and the underlying insole or insert are of particular importance because this construction enhances the ventilation and breathing properties of the shoe which is of paramount importance in my invention. Particularly in the instance of the ordinary insole, as shown, for example, in Figures 1 and 4, the perforations therein in combination with the overlying perforations in the resilient pad provide an air cell which is in part resilient and by means of which increased volume is provided so that added breathing and coolness is obtained in the shoe in addition to the enhanced flexibility of the construction.

In the foregoing I have given a number of specific examples of my invention. Various modifications and modified forms of the constructions here shown may be utilized to obtain the new and unexpected results set forth and will be obvious to those skilled in the art. I intend therefore to be limited not by the specific description here set forth but only by the claims hereto appended.

I claim:

1. In combination, a resilient pad and an insole, an opening in the forepart of said insole, a resilient insert disposed and secured in said opening in said insole, perforations in and through said resilient pad and perforations in said resilient insert, said perforations in said resilient pad being superimposed over said perforations in said insert, and lugs projecting downwardly from the underside of said resilient pad, recesses in said resilient insert adapted to receive and engage said downwardly projecting lugs for securing said resilient pad to said resilient insert.

2. In combination, a resilient pad and an insole, an opening in the forepart of said insole, a resilient insert disposed and secured in said opening in said insole, perforations in and through said resilient pad and perforations in said resilient insert, said perforations in said resilient pad being superimposed over said perforations in said insert, and lugs projecting downwardly from the underside of said resilient pad, recesses in said resilient insert adapted to receive and engage said downwardly projecting lugs for securing said resilient pad to said resilient insert, and a metatarsal arch support projecting upwardly from the upper surface of said resilient pad in the region of the metatarsal arch.

MEYER MARGOLIN.
